INVENTOR.
NORMAN E. OLIN

BY *Peter E. Boesky*

ATTORNEY.

UNITED STATES PATENT OFFICE

2,467,048

CIGARETTE CASE

Norman E. Olin, New York, N. Y.

Application April 27, 1948, Serial No. 23,598

4 Claims. (Cl. 312—47)

1

This invention relates to new and original improvements in cigarette cases or holders, and has for its purpose to provide a transparent article, preferably made from plastic, which will clearly display the cigarettes placed in said holder, and which will provide for an automatic expelling of such cigarettes without touching the latter.

The device is preferably made as an upright holder or casing, and may thus, due to its unique construction and according to the material it is made from, provide a beautiful adornment, when placed upon a table or pedestal.

Furthermore, said holder may be provided with special embellishing features, such as an artistically formed border around its outer edges, or the edges of an expelling frame forming part of the device.

With the above and other objects in view, this invention consists of the novel features of construction, combination and arrangement of parts, hereinafter fully described, claimed and illustrated in the accompanying drawings forming part of this application, and in which similar characters of reference indicate corresponding parts in all views, and in which—

Figure 1 is a somewhat perspective elevation of my device.

Figure 2 is a vertical transverse section of my device shown in Figure 1.

Figure 3 is a transverse section taken on the line 3—3 in Figure 2.

Figure 4 is a view similar to Figure 1, but showing a slight modification in the construction of my device.

Figure 5 is a vertical transverse section of my device shown in Figure 4; while

Figure 6 is a transverse section taken on the line 6—6 in Figure 5.

Referring more particularly to the drawings, the numerals 10, 10 indicate two spaced upright parallel walls integral with a base 11, the numeral 12 indicates a rectangular frame vertically slidable between the walls 10, 10.

The sides 13, 13 of the frame 12 are of a substantially cylindrical shape and are thicker in cross section than the space between said walls, although a small curved portion 15, 15 upon the inner side, of each of said cylindrical frame members extends a small distance in between the walls 10, 10 as shown especially in Figure 3, whereby the frame 12 is guided in an up or downward movement relative to the holder proper. The frame 12 has a top portion 14, which may be of the same shape and thickness as the side frame members 13, 13. At the bottom the frame mem-

2

bers 13, 13 are connected by a preferably flat, crosswise arranged member 16, which snugly but slidably fits within the walls 10, 10, and is adapted by manipulation of the frame 12 to move up and down within said walls and at the same time carry a cigarette 17, of which a number may be placed between said walls, to the top of the latter, whereupon the uppermost cigarette, when the top member 14, as part of the frame 12, is lifted upward, sufficiently, will automatically be disposed in one of the curvatures 20, 20 in the top of each side of said walls 10, 10.

The device, as shown in Figures 4, 5 and 6, is identical in construction to the one hereinbefore described, with the exception that the walls 10', 10' are near their outer side edges provided with vertical, slight curvatures 18, 18 shown in Figure 6 in which the center portions of the cylindrically shaped side frame members 13, 13 may slide; a small portion of the sides of said frame members extending outside the walls, as shown at 19.

It is obvious that changes may be made in the form, construction and arrangement of the several parts, as shown, within the scope of the appended claims, without departing from the spirit of the invention, and I do not, therefore, wish to limit myself to the exact construction shown and described herein.

30 What I claim as new, and desire to secure by Letters Patent of the United States, is:

1. In a device of the class described, a base, two spaced, upright parallel walls integral with the latter, a rectangular frame vertically slidable relative to said walls and forming an enclosure with the latter, a crosswise member forming the bottom of said frame and being slidable vertically between the walls, and a longitudinally curved recess at the top of each wall, substantially as and for the purpose set forth.

2. In a device of the class described, a base, two spaced upright parallel walls integral with the latter, a rectangular frame vertically slidable between the edges of said walls, and forming a closure with the latter adapted to receive cigarettes therein, the side members of said frame being of greater cross-sectional width than the distance between the walls, and a crosswise member at the lower end of the frame adapted to slide between said walls, whereby to engage and expel a cigarette, when the frame is moved in an upright direction.

3. A cigarette holder comprising a base, two spaced, upright parallel walls integral with the latter, a rectangular frame, the side members

of the latter being adapted to slide partially between said walls, said frame having a crosswise member adapted to slide between said walls and engage and eject a cigarette, the top portions of each wall being formed with a curvature adapted to receive the ejected cigarette.

4. In a device of the class described, a base, two spaced, upright parallel walls integral with the latter, said walls being formed with curved recesses in their opposite inner surfaces upon 10 each side thereof and near the edges, a rectangu-

lar frame adapted to form a compartment with said walls, the side members of said frame being adapted to slide in said recesses, a crosswise member at the bottom of said frame adapted to slide within said walls, the latter being formed with curved depressions at the top thereof, substantially as and for the purpose set forth.
